ABSTRACT OF THE DISCLOSURE

A dust seal and pressure element for the magnet assembly of a permanent magnet equipped loudspeaker, the magnet assembly including a magnet frame or pot, a permanent magnet secured within said pot, and a pole piece secured to the permanent magnet within the pot.

BACKGROUND OF THE INVENTION

In magnet assemblies of most permanent magnet speakers, the magnet is of generally cylindrical form and adhered at one end to the inner surface of a pair of spaced walls of the magnet frame or pot, the opposite wall of the pot having an opening therethrough, axially aligned with the magnet. A generally cylindrical pole piece has an outer end disposed concentrically within said opening and a circumferential flange at its inner end, the inner end being adhered to the adjacent end of the magnet. A generally cup-shaped hollow dust seal element encompasses the pole piece, and at its smaller diameter end has sealing engagement with an annular shoulder defined by the flange of the pole piece, the marginal edge of the seal element engaging the inner surface of said opposite wall of the pot radially outwardly of the opening therethrough, whereby to exclude dust or other foreign matter from the annular space between the pole piece and the opening in the pot wall.

Heretofore, dust seals on shields have been generally stamped and formed from thin sheet material, such as brass, paper and the like, having relatively low resilience. The use of a metal dust shield or seal necessitates the maintenance of extremely close dimensional tolerances in the space between the opposite walls of the pot, and the axial dimensions of the magnet, pole piece flange and the seal, if effective sealing is to be achieved. It is well known that, in the mass production of parts, the costs thereof rise as the dimensional tolerances are narrowed. Further, in the production and handling of the metal seals, nicks and burrs often occur in the sealing portions thereof, and often small pieces or slivers of foreign matter adhere thereto, largely destroying the sealing qualities thereof.

In the assembly of the above-described speaker magnet assemblies, the magnets are secured to the pot and to the pole piece by suitable adhesive which is puddled around the opposite end portions of the peripheral surface of the magnet, and on the adjacent portions of the pole piece flange and the magnet engaged wall surface of the pot. In many instances, it has been found that, due to rough handling or vibration, the adhesive fails to hold the parts together, and the speaker is rendered inoperable. Efforts have been made to apply adhesive to the opposite end faces of the magnet whereby a much improved bond is formed therebetween and the pole piece and pot, and to axially contract or compress the metal seal sufficiently to permit proper inter-position of the magnet between the pole piece and pot wall without rubbing or scraping the adhesive from the end surfaces of the magnet, to the end that, release of the sealing element will permit the same to axially expand and press the magnet between the pole piece and the pot wall to achieve an effective bond.

2

Without maintaining costly tolerances, as set forth above, either the seal is axially contracted or compressed beyond its elastic limit, when the axial dimensions of the magnet is unduly long, so that it will not expand sufficiently to apply proper sealing pressure to the pole piece and pot, or a given magnet will be too short to properly fill the gap between the pole piece and the opposite wall surface. In such event, a magnet of proper axial length must be selected from a supply thereof, resulting in loss of assembly time.

10

SUMMARY OF THE INVENTION

The primary object of this invention is the provision of a combination dust seal and pressure element which can be axially contracted or compressed to a substantially higher degree than heretofore without exceeding its limit of elasticity, so that component parts of a speaker magnet assembly can be prefabricated with greater dimensional tolerance than heretofore, and be assembled easily and more effectively adhered together, and which, when the parts are assembled, will provide a more effective seal. To this end, I provide a hollow cup-shaped member having an axial opening therethrough for reception of a pole piece, and an outer annular surface portion adjacent said axial opening for sealing engagement with an annular shoulder on the pole piece adjacent its inner end. The marginal edge of the cup-shaped member is adapted to have sealing engagement with the inner wall surface of the magnet pot radially outwardly of the pole piece receiving opening in the pot wall. The cup-shaped member is made from non-metallic material having a substantially high elastic resiliency or memory, capable of being axially contracted or compressed sufficiently to enable a speaker magnet to be interposed between the pole piece and the opposite wall of the magnet pot with generous clearance between the ends of the magnet and said pole piece and pot wall, without exceeding the elastic limit of the cup-shaped member. The elastic resiliency or memory of the cup-shaped member is such that, when released from its axially contracted state, the member axially expands sufficiently to exert axial sealing pressure against the shoulder and magnet pot and bonding pressure upon the magnet to hold the magnet against movement during drying or curing of adhesive applied to the opposite end surfaces thereof and in contact with the pole piece and pot wall surface. The marginal edge portion of the member in engagement with the adjacent wall of the pot radially expands during axial contraction of the member and radially contracts during axial expansion of the member.

DESCRIPTION OF THE DRAWINGS

Referring to the drawings, in which like reference characters indicate like parts:

FIG. 1 is a view in top plan of the magnet pot assembly including the dust seal and pressure element of this invention, and illustrating a step in the method of assembly, some parts being broken away and some parts being shown in section;

FIG. 2 is a transverse section taken substantially on the line 2—2 of FIG. 1;

FIG. 3 is a view corresponding to FIG. 2 but showing a different position of some of the parts;

FIG. 4 is a fragmentary view partly in elevation and partly in section, taken substantially on the line 4—4 of FIG. 2;

FIG. 5 is a view in perspective of a dust seal and pressure element produced in accordance with this invention;

FIG. 6 is a fragmentary section taken on the line 6—6 of FIG. 5;

70

FIGS. 7 and 8 are views corresponding to FIG. 5 showing modified forms of dust seal and pressure element; and

FIGS. 9 and 10 are fragmentary sections taken on the lines 9—9 and 10—10 of FIGS. 7 and 8 respectively.

Referring with greater detail to the drawings, a cross sectionally rectangular magnet frame or pot is indicated generally at 1, the same being formed from a bar of iron or steel to provide a tube having spaced parallel side walls 2 and 3 and end walls 4. The side wall 2 is provided with a generally central opening 5 for reception of a cylindrical pole piece 6, the outer end portion of which is disposed within the opening 5, the inner end of the pole piece 6 being formed to provide a radially outwardly projecting circumferential flange 7, which defines an annular shoulder 8. A generally cylindrical permanent magnet 9 is interposed between the inner end of the pole piece 6 and the side wall 3 and is adhered to the pole piece 6 and side wall 3 by layers of adhesive 10. The outer end portion of the pole piece 6 is concentric with the opening 5 to provide an annular passage 11 for the usual loudspeaker voice coil, not shown. As is well known, the voice coil moves axially in the annular passage 11 with very little clearance therebetween and the pole piece 6 and wall of the opening 5. Hence, it is important that dust or other foreign material be excluded from the passage 11, whereby to prevent the same from upsetting the operating characteristics of the speaker or rendering the same inoperative altogether. Therefore, a hollow generally cup-shaped dust seal 12 is interposed between the shoulder 8 of the pole piece 6 and the inner surface of the side wall 2 of the pot. When the above-described pot assembly is used to complete a loudspeaker, foreign matter is prevented from entering the annular passage 11 from the exterior of the pot 1 by other portions of the speaker, not shown, but attached to the outer surface of the wall 2.

The dust seal 12 is formed or molded from suitable non-metallic material having substantial elastic resiliency, or memory, such as various commercial plastics, glass fibers, or rubber, and is provided at its smaller diameter inner end with an axial opening 13 for reception of the pole piece 6. As shown, an annular surface portion 14 adjacent the opening 13 sealingly engages the shoulder 8 of the pole piece 6, the outer surface of the member 12 between the annular surface portion 14 and the marginal edge 15 thereof being of generally spherical shape. As shown by broken lines in FIG. 3, the axial dimension or length of the cup-shaped seal or member 12 is greater than the axial dimension thereof in the completed magnet assembly.

In assembling the magnet assembly, the member 12 is placed on the pole piece 6, after which the pole piece is inserted through the opening 5 in the pot wall 2 with the marginal edge 15 of the seal or cup-shaped member 12 engaging the inner surface of the wall 2. A centering sleeve 16 is then inserted inwardly through the annular passage 11 to properly locate the pole piece 6 concentric with the opening 5. The pole piece 6 and cup-shaped member 12 are then moved in a direction outwardly of the opening 5 to cause the member 12 to be axially contracted or compressed between the shoulder 8 and the pot wall 2. This may be accomplished by any suitable means, such as a bifurcated pressure element shown by dotted lines in FIGS. 1, 2 and 4 and indicated at 17. As shown in FIGS. 1 and 2, axial contraction of the member 12 results in radial expansion of the marginal edge portion thereof, permitting the member 12 to be axially contracted a substantial amount from its normal axial length. With the member 12 thus contracted or axially compressed, adhesive material 10 is applied to opposite ends of the magnet 9 and the same is placed within the pot between the pot wall 3 and the inner end of the pole piece 6 in axial alignment with the pole piece 6. Although not shown, it may be assumed that any suitable centering

means, such as a template or the like, may be used to properly locate the magnet 9. When the magnet 9 is properly placed, the pressure element 17 is removed, permitting the seal or cup-shaped member 12 to axially expand to exert bonding pressure on the flange 7 against the adjacent end of the magnet 9 and to press the magnet 9 into bonding pressure with the pot wall 3. The centering sleeve 16 may be then removed and the magnet assembly used in the building of a loud speaker.

It will be appreciated that, in view of the elastic nature of the member 12, which permits the portion thereof of adjacent the marginal edge 15 to radially expand, the member 12 may be contracted axially to a far greater extent than the heretofore used metallic dust shields, before the elastic limit thereof is reached. Thus, in prefabricating the several parts of the magnet assembly, the dimensional tolerances of the pot 1, flange 7, magnet 9 and shield or member 12, in a direction axially of the pole piece 6 and magnet 9, need not be critical as is the case when a metallic shield is used.

In present practice, the commercial tolerance in the axial dimension of magnets is plus or minus five one-thousandths inch, that of the axial dimension of the pole piece flange plus or minus at least one one-thousandth inch, and that of the inside dimension of the pot frame being plus or minus five one-thousandths inch. Thus it may be readily understood that, with such a large range of dimensions, the metallic dust shields heretofore used, having a relatively short range of axial expansion and contraction, have necessitated costly selection of magnets, pole pieces and magnet ports, from supplies thereof, to obtain close fitting magnet assemblies. Further, by molding or otherwise fabricating the member 12 from non-metallic materials, as above indicated, the necessity for degreasing and cleaning the seal prior to assembly, is eliminated. Moreover, the elastic resilience of the material causes the seal 12 to make effective sealing contact with the shoulder 8 and adjacent inner surface of the pot wall 2, even though the surface of the pot wall 2 is rough or uneven.

A very definite advantage in the use of the member 12 over a metallic dust seal resides in the fact that it enables the adhesive 10 to be applied to the entire end faces of the magnet 9, whereby maximum area bonding is achieved between the magnet 9 and pole piece 6 and wall 3.

If desired by those who have established assembly procedures and apparatus, the layers of adhesive 10 may be omitted, and the magnet 9 may be adhered to the magnet pot 3 and pole piece 6 by puddling adhesive around opposite end portions of the magnet and adjacent surface portion of the pole piece and magnet pot as heretofore done.

As shown in FIG. 1, the bifurcated pressure element 17 engages the generally spherical surface of the cup-shaped shield member 12 just radially outwardly of the flange 7. The modified form of cup-shaped member shown in FIG. 7 and indicated at 18, is formed to provide a relatively larger diameter annular surface portion 19 radially outwardly of the central opening 20 of the member 18, for engagement with the bifurcated pressure element 17.

The modified form of dust seal shown in FIG. 8, and indicated at 21, is formed to provide a pair of diametrically opposed surface portions 22 for engagement of the pressure element 17, radially outwardly of the central opening 23 of the member 21.

It will be appreciated that other suitable means may be employed for axially contracting the dust seals of this invention, such as a magnetic chuck or the like, not shown, applied to the outer end of the pole piece 6, if desired.

While I have shown several embodiments of dust seal and pressure element, it will be understood that the same is capable of further modification without departure from the spirit and scope of the invention, as defined in the claims.

What is claimed is:

1. A dust seal and pressure element for a speaker magnet assembly including, a magnet pot having spaced side

walls and an opening through one of said side walls, a pole piece extending axially through said opening and having a flanged inner end defining an annular shoulder in axially inwardly spaced relation to said opening, and a magnet between said flanged end of the pole piece and the other one of said side walls; said element comprising a hollow generally cup-shaped member having an axial opening for reception of a pole piece and an outer annular surface adjacent said opening for sealing engagement with said annular shoulder, said member having a marginal edge for sealing engagement with said one of the walls of said pot radially outwardly of said opening, said cup-shaped member being of non-metallic elastic resilient material and having a modulus of elasticity such that the member may be compressed axially a substantial proportion of its normal axial dimension without exceeding the elastic limit of the member, said member, adjacent its marginal edge, being radially expansible and contractable responsive to axial compression and expansion respectively of said member.

2. The dust seal and pressure element defined in claim

- 5 1, in which said annular surface includes flat transverse surface portions extending radially outwardly from said axial opening.
3. The dust seal and pressure element defined in claim 1, in which said cup-shaped member is fabricated from synthetic plastic material having elastic memory.
4. The dust seal and pressure element defined in claim 2, in which said member is of generally spherical shape between said annular surface and the marginal edge of the member.
